BERNARD O. FJORKENSTAD, OF FINGAL, SOUTH DAKOTA.

PHOTOGRAPHIC-PRINTING MACHINE.

1,125,680.

Specification of Letters Patent.

Patented Jan. 19, 1915.

Application filed June 5, 1914. Serial No. 843,179.

To all whom it may concern:

Be it known that I, BERNARD O. FJORKENSTAD, a citizen of the United States, and a resident of Fingal, in the county of Barnes and State of North Dakota, have invented a new and Improved Photographic-Printing Machine, of which the following is a full, clear, and exact description.

This invention relates to improvements in photographic printing machines designed especially for printing on developing papers and the primary object of the invention is to provide a machine designed especially for printing on developing paper where speed, accuracy and uniformity of results are desired whether used with natural or artificial light.

A further object of the invention is to provide an improved photographic printing machine which is primarily intended to be placed in the lower part of an ordinary window and to indirectly receive the light rays, the window being covered around the machine so that no light can enter the room and the upper part of the window being equipped with a red or orange colored light which will only allow non-actinic rays of light to enter the room and still enable the operator to see his work without danger of injuring the negative or sensitized paper.

A still further object of the invention is to provide an improved photographic printing machine which includes an inclosure or frame having a shutter movable in front thereof to admit or exclude the light, either natural or artificial, a holder for the negatives including a movable part or lever cooperative with means for opening the shutter so that while the negative is being placed in position only the non-actinic rays will be admitted to illuminate the area in the room and the negative sufficient to permit the operator to properly adjust the negative and sensitized paper and whereby a further movement of the lever will open the shutter to admit the printing light while the release of the lever permits the shutter to close by gravity when the printing operation is completed.

Still further objects of the invention, among others, are to provide novel means for holding the negative and developing or sensitized paper in position and to accurately adjust the same, as well as to provide a novel construction permitting the operator to conveniently do vignetting by blotting out portions of the negative or to regulate the

intensity of the light which is reflected on to the negative.

With the above and other objects in view, the invention resides in the peculiar combination and arrangement of parts to be hereinafter more fully described, illustrated and claimed, it being also an object to provide a device which is simple in construction, durable and efficient in operation and not likely to get out of working order.

Reference is to be had to the accompanying drawings forming a part of this specification, in which similar characters of reference indicate corresponding parts in all the views, and in which—

Figure 1 is a perspective view of my improved photographic printing machine with portions thereof broken away; Fig. 2 is a plan view of the machine partly in section as shown in Fig. 3; Fig. 3 is a sectional view taken on the line 3—3 of Fig. 2; Fig. 4 is a view similar to Fig. 3 but showing the lever for actuating the negative and paper-holding pad or platen to move to a position to cause the opening of the shutter for admitting light to the machine; Fig. 5 is a sectional view taken on the line 5—5 of Fig. 3; Fig. 6 is a sectional view taken on the line 6—6 of Fig. 4 but showing the lever and pad carried thereby raised and the shutter lowered.

In carrying my invention into practice the device is installed in the lower part of a window frame 10 or adjacent to any other suitable source of light, either natural or artificial, but in the present instance supported upon a shelf or the like 11 constituting a support which is built into the window or attached to it by means of brackets or otherwise. The lower sash is indicated by the numeral 12 and the lower half of the window is entirely darkened around the machine so that no light can enter the room through this part of the window, while the upper half of the window is equipped with a yellow or ruby light of sufficient size to permit the operator to see his work, with the part of the window surrounding said light darkened to exclude actinic rays.

The machine is made up of an inclosure 13 which is provided with side and bottom cleats 14 at a spaced distance from its surrounding front edge to fit in the window frame and serve as attaching means for the dark covering between the same and the window frame, such covering being made of

dark paper, cloth or glass. This inclosure is of rectangular construction except for an inclined bottom part 15 and is elongated inwardly, the outer side of the inclosure being 5 open and supporting a frame 16 vertically above the inclosure at the front. The inclosure and frame are provided with vertically alined grooves forming guideways 17 which receive a shutter 18 for vertical sliding movement therein, said shutter being of darkened material such as pasteboard except for a small yellow light or screen 19 for excluding actinic rays and permitting illumination by non-actinic rays only there- 10 through. The interior of the inclosure forms a reflector, being painted or covered with a reflecting material such as white enamel including an inclined partition 20 which is disposed at a proper angle therein 15 to reflect the rays of light vertically toward the top of the inclosure and which if desired may be in the form of a mirror or burnished metal. The inside or back of the inclosure is indicated by the numeral 21 20 the same including a hinged door 22 at the top portion which is adapted to swing rear- 25 wardly, said door when open communicat- ing with the space beneath the reflecting partition 20 and the bottom portion of the 30 inclosure.

Transversely of the inclosure in rear of the frame 16 and depending into the inclosure is a cross bar 23 which serves as a stop member to limit the downward or closing move- 35 ment of the shutter by gravity due to the contact of a transverse strip or cleat 24 on the inner side and at the upper edge of the shutter, therewith. At the opposed inner sides of the inclosure horizontal guide strips 40 25 are provided forming guideways at the top part of the inclosure to removably support and hold a pair of spaced plates 26 which are preferably of glass, the plates being thus limited against inward movement 45 by the cross bar and being held from outward displacement by the door when closed and secured in this position as by means of fasteners 27 at its opposite ends. The co-acting edges of the inner portion 21 and the 50 door 22 are provided with center recesses 28 communicating with each other to accom- modate the crank portion 29 of a crank shaft 30 journaled or pivotally mounted transversely through the inclosure as by 55 means of spaced center bearings 31 and outer bearings 32. The crank 29 normally projects outward and is accommodated in the notch formed by the co-acting recesses while the ends of the crank shaft are pro- 60 vided with forwardly projecting arms 33 which are inclined downwardly and forwardly and are in turn connected at their free ends by rods 34 to the extremities of a cross head 35 fixed to the strip 24.

65 The door 22 is provided with a vertical

opening 36 communicating with the bottom recess to receive a headed plunger 37 for vertical movement therein, the plunger having a prong or fork-shaped lower end, as shown at 38, to produce a yoke to straddle 70 the crank of the shaft and rest thereon. Due to the weight of the shutter and the fact that the latter normally lowers by gravity, the crank will support the plunger in an upwardly projected position, this being 75 effected by rotation of the crank shaft due to the downward movement of the arms 33 by the connection thereof with the shutter through the medium of the rods 34, while in order to open the shutter the plunger is de- 80 pressed to cause the opposite movement of the parts from that described.

In order to hold the negative and de- 85 veloping paper in position when the paper is to be printed, a pair of spring clamps 39 are provided, the same being pivotally connected to brackets 40 carried by the cross bar 23 preferably near the ends thereof and curving downwardly to engage an angular paper guide 41 in the form of a square. 90 This paper guide is engaged over the negative 42 after the latter is placed glass side down on the uppermost plate 26 and then the guide is placed in position over two edges of the negative to hold the latter 95 against movement when the springs are en- gaged on the holder to exert downward pressure on the latter. Pivoted to the cross bar 23 intermediately the length of the lat- 100 ter is a lever 43, the hinge of the lever hav- ing inwardly projecting holding arms 44 to the free ends of which a pad or platen 45 constituting a paper holding means is piv- 105 otally connected, the inner face of the platen being padded or covered with cloth, 110 as shown. Carried by the platen and pro- jecting upwardly therefrom is a threaded stem 46 which passes through an aperture in the lever, while an expansible coiled spring 47 is engaged on the stem between 115 the platen and the lever to normally space the latter from the platen, such spacing be- 120 ing capable of adjustment by means of a thumb nut 48 threaded on the stem above the lever.

In operating the machine after it has been properly installed the lever is raised, as shown in Fig. 1 of the drawings, to engage between a spring clip 49 which is of U- 125 form with out-turned leg portions and which is carried by the top portion of the frame 16 intermediate the width of the lat- 130 ter to project inwardly. The platen is thus raised with the lever although the spring connection between the two permits move- ment of the lever relative to the platen when the same is lowered, and the negative being placed in position on the top of the inclosure and held by the paper guide and clamping springs in the manner described, 130

a sheet of printing paper is then placed on the negative against the guide and the lever lowered to bring the pad or platen with it striking and holding the paper firmly 5 against the negative. During this time the shutter with its translucent light 19 of yellow, orange or ruby fabric is lowered so that non-actinic rays only are allowed to enter the machine to permit the operator to properly 10 place the negative and paper in position without injuring the same. The lever is then in the position shown in Fig. 3 of the drawings and by moving it downwardly to engage the plunger the latter may be depressed, as shown in Fig. 4 of the drawings, to swing the crank shaft in its bearings and elevate the arms 23 so as to raise or open the shutter and permit the entrance of actinic light rays for the proper time required 15 to print the paper, when upon the lever being raised or released and elevated by the spring 47, the shutter will drop by gravity to shut off the printing light rays and the plunger elevated. While the shutter is open the rays entering through the front of the inclosure will be reflected by the interior walls thereof and particularly the inclined portion or reflector 20, upwardly on to the negative.

20 Although the plates 26 are preferably of transparent glass so that the absorption of light reflected is almost *nil*, the intensity of the light may be regulated by substituting a translucent or ground glass for the lower plate should the light be too strong, as for instance for thin negatives. In lieu 25 of substituting the lower plate by a translucent plate which permits the entrance of actinic rays, vignetting may be conveniently carried on by inserting a piece of tissue paper or other similar light-softening material between said plates by opening the door 22, or by simply cutting a hole the desired size in a piece of light-proof paper and inserting the same between the plates or lights, the intensity of the light may be 30 regulated or softened. When the printing operation is completed the lever is raised to a vertical position and the paper and negative released and removed.

In order to use the device and as a retouching or spotting device, the plunger is depressed to raise the shutter and the lever is moved to a vertical position or raised and is provided with an angular bracket 50 to engage beneath the strip or cleat 24 to support the shutter while admitting the light either natural or artificial to permit the operator or photographer to view the work.

55 A pair of shelves 51 are carried by the inclosure, one at either side in alinement with the top of the inclosure to support utensils and materials used during the printing and retouching operations.

60 Special advantages are held to lie in the supporting of the lever by the spring so that after the lever has been moved to bring the platen in contact with the paper, further movement of the same compresses the spring and thus provides for a yielding movement between the paper and the negative. In this manner the opening of the shutter by depression of the plunger is also obviated until such time as the negative and the printing paper are properly secured in 70 position, the two operations being successive, while when the lever is raised the shutter is automatically lowered by releasing the plunger and actinic light rays are thus excluded or shut out so that further handling 75 of the negative and printing paper may continue without danger of injury thereto.

The machine is simple and cheap in construction and has no complicated parts so that more accurate and uniform results are 80 assured.

Having thus described my invention, what I claim is:—

1. A photographic printing machine, comprising an inclosure, said inclosure having an opening at its front portion to permit the entrance of light to the inside thereof, a shutter vertically movable in front of the inclosure and above the same, said shutter having a screen for excluding actinic rays 90 when the shutter is over the opening, means at the top of the inclosure for supporting a negative with printing paper thereon, means for moving the shutter, and movable means for holding the paper and negative and successively operating the shutter moving means to open the shutter.
2. A photographic printing machine, comprising an inclosure, said inclosure having an opening at its front portion to permit the entrance of light to the inside thereof, a shutter vertically movable in front of the inclosure and above the same, said shutter having a screen for excluding actinic rays 100 when the shutter is over the opening, means at the top of the inclosure for supporting a negative with printing paper thereon, means for moving the shutter, and movable means for holding the paper and negative and successively operating the shutter moving means to open the shutter, said shutter being adapted to close by gravity, whereby when said holding means is disengaged from the shutter opening means the shutter will close.
3. A photographic printing machine, comprising an inclosure adapted for disposal adjacent to a source of light, a frame at the front portion of the inclosure, a shutter movable in the frame to cover and uncover the front portion of the inclosure, a reflector in the inclosure above the bottom thereof, a plurality of spaced plates in the top of the inclosure to permit the entrance of light therethrough and form a support for a negative and paper to be printed therefrom,

5 a lever pivoted to the frame and having a padded member to engage and hold the paper and negative, a crank shaft journaled transversely through the inclosure at the
10 inner end thereof and having forwardly projecting arms connected to the shutter, a plunger operating through the inner part of the inclosure and engaging the crank portion of the shaft to rotate the latter upon the plunger being pressed to open the shutter, and means to hold the lever with its
15 engaging member in a raised position.

4. In a photographic printing machine, a substantially rectangular inclosure having an open front portion and an open top portion, cleats secured to the sides and bottom of the inclosure to permit the attachment of the latter within a window frame with light-excluding means therearound, a frame above the front end of the inclosure, said frame and inclosure having alined grooves forming guideways, a shutter vertically movable in said guideways and having a translucent screen permitting the entrance of non-actinic rays to the interior of the inclosure receiving light and said inclosure being interiorly provided with means to reflect the light to the top thereof, a door at the inner side of the inclosure adjacent the upper edge thereof, a pair of transparent plates removably supported in the top of the inclosure and adapted to support the negative and paper to be printed and to receive vignetting plates therebetween, means to removably retain said negative in position and including a guide for the paper, a plunger vertically movable in the door, a crank shaft pivotally mounted through the inclosure and engageable by the plunger whereby depression of the latter will rotate the shaft, arms projecting forwardly and downwardly from the shaft, rods connecting the arms to the shutter for raising the latter upon the plunger being depressed, said shutter being adapted to close by gravity and raise the plunger, and paper holding means carried by the frame and operative over the plates.

5. In a photographic printing machine, a substantially rectangular inclosure having an open front portion and an open top portion, cleats secured to the sides and bottom of the inclosure to permit the attachment of the latter within a window frame with light-excluding means therearound, a frame above the front end of the inclosure, said frame and inclosure having alined grooves forming guideways, a shutter vertically movable in said guideways and having a translucent screen permitting the entrance of non-actinic rays to the interior of the inclosure, means within the inclosure whereby light rays entering therein will be reflected to the top thereof, a door at the inner side of the inclosure adjacent the upper edge thereof, a pair of transparent plates removably sup-

ported in the top of the inclosure and adapted to support the negative and paper to be printed and to receive vignetting plates therebetween, means to removably retain said negative in position and including a 70 guide for the paper, a plunger vertically movable in the door, a crank shaft pivotally mounted through the inclosure and engageable by the plunger whereby depression of the latter will rotate the shaft, arms projecting forwardly and downwardly from the shaft, rods connecting the arms to the shutter for raising the latter upon the plunger being depressed, said shutter being adapted to close by gravity and raise the plunger, a 75 lever pivoted to the front portion of the inclosure, a pad movable therewith and yieldingly connected thereto, said lever being adapted to be lowered whereby the pad will engage the paper to hold the latter in position, and means carried by the frame to hold the lever in an upright position.

6. In a photographic printing machine, a substantially rectangular inclosure having an open front portion and an open top portion, cleats secured to the sides and bottom of the inclosure to permit the attachment of the latter within a window frame with light-excluding means therearound, a frame above the front end of the inclosure, said frame and inclosure having alined grooves forming guideways, a shutter vertically movable in said guideways and having a translucent screen permitting the entrance of non-actinic rays to the interior of the inclosure, 90 said inclosure being adapted to receive light rays and interiorly provided with a reflector to reflect the light rays to the top thereof, a door at the inner side of the inclosure adjacent the upper edge thereof, a pair of transparent plates removably supported in the top of the inclosure and adapted to support the negative and paper to be printed and to receive vignetting plates therebetween, means to removably retain said negative in position and including a guide for the paper, a plunger vertically movable in the door, a crank shaft pivotally mounted through the inclosure and engageable by the plunger whereby depression of the latter will rotate the shaft, arms projecting forwardly and downwardly from the shaft, rods connecting the arms to the shutter for raising the latter upon the plunger being depressed, said shutter being adapted to 100 close by gravity and raise the plunger, a lever pivoted to the front portion of the inclosure, a pad movable therewith and yieldingly connected thereto, said lever being adapted to be lowered whereby the pad will engage the paper to hold the latter in position, said lever being adapted for further movement to engage the plunger and to depress the same and open the shutter, and means carried by the lever to engage the 105 110 115 120 125 130

shutter to hold the latter open when the pad is raised.

7. A photographic printing machine, comprising an inclosure having an inclined bottom portion near its inner end, an open front portion and a top portion, an inclined partition in the inclosure to cause the reflection of light toward the top, said top portion permitting the passage of light there-through, a shutter for the front portion of the inclosure, depressible means at the inner end of the inclosure for opening the shutter and adapted upon being released to permit the shutter to close by gravity, an angular guide adapted to engage a negative on the top, means carried by the inclosure to hold the guide in position, a lever pivoted to the inclosure at the front and having arms projecting inwardly therefrom, a platen having a padded engaging face, said platen being pivoted to the arms and having a stem adjustably connected to the lever, means between the lever and the platen for raising the lever, said lever being adapted to be lowered to engage the paper to be printed whereby the latter is held against the negative and in proper alinement by the guide, further downward movement of the lever engaging said shutter operating means, means to hold the lever in a disengaged position, means to support the shutter in an open position, and shelves at opposite sides of the inclosure. 25 30

In testimony whereof I have signed my name to this specification in the presence of 35 two subscribing witnesses.
